UNITED STATES PATENT OFFICE

ALBERT H. TAYLOR, OF WASHINGTON, DISTRICT OF COLUMBIA, ASSIGNOR TO WIRED RADIO, INC., OF NEW YORK, N. Y., A CORPORATION OF DELAWARE

HIGH-FREQUENCY OSCILLATION GENERATOR

Application filed December 22, 1928. Serial No. 327,937.

This invention relates to piezo electric crystal frequency control of high frequency oscillation generators generally. More specifically, this invention relates to piezo electric crystal frequency control of high frequency oscillation generators wherein the generator is to produce oscillations of any one of a plurality of frequencies.

An object of this invention is to provide means in a high frequency oscillation generator employing piezo electric crystal frequency control, whereby the frequency of the oscillations generated may be readily changed.

Another object of this invention is to provide means in a piezo electric crystal frequency controlled high frequency oscillation generator whereby the frequency of the oscillations generated may be readily changed from one predetermined constant value to another without destroying the effect of piezo electric crystal frequency control.

A further object of this invention is to provide means in a piezo electric crystal frequency controlled oscillation generator whereby any one of a plurality of piezo electric crystals may be readily used to control the frequency of the oscillations generated.

An ancillary object of this invention is to connect a plurality of piezo electric crystals into a circuit arrangement with an electron tube oscillation generator having a plurality of grid electrodes whereby any one of the piezo electric crystals may be readily used to control the frequency of the oscillations generated.

A further object of this invention is to provide a piezo electric frequency controlled high frequency oscillation generator circuit of large output.

Other features of this invention will be apparent to those skilled in the art to which this invention appertains, from the following specification and claims.

According to this invention a plurality of piezo electric elements ground to different radio frequencies are connected to the electrodes of a four electrode electron tube high frequency oscillation generator. A frequency selective circuit is connected to the filament and anode of the electron tube. This

selective circuit is tuned to the frequency of any one of the piezo electric elements whereby the electron tube oscillation generator generates high frequency oscillations corresponding to the frequency of the piezo electric element selected.

In the drawing, the figure illustrates a circuit arrangement embodying this invention.

Referring to the drawing in detail, the reference character 1 designates a thermionic vacuum tube in which are incorporated the anode 2, grid electrodes 3 and 4 and filament or cathode electrode 5. The thermionic vacuum tube may be of the ordinary two grid type or it may be of the shield grid type; in the latter case, the shield grid electrode corresponds to electrode 3 of the figure. Reference character 6 designates the source of supply for the cathode 5. A choke coil 7 is connected to the control electrode 4 and biasing source of potential 7'. The control electrode 3 is connected to one terminal of a choke coil 8. The other terminal of the coil 8 is connected to a voltage divider 10 which is connected across the source of anode potential 11. The sources of potential 7' and 11 are connected to the filament 5. A capacity 9 is connected across the source of supply 11 and furnishes a high frequency circuit across the source. An inductance 12 having a capacity 13 associated therewith is connected to the anode electrode 2 of the thermionic vacuum tube. Piezo electric elements Q_1 , Q_2 and Q_3 are connected to the grid electrodes of the thermionic vacuum tube 1. Element Q_1 is connected between the electrode 3 and the cathode 5; element Q_2 is connected between the electrode 4 and the cathode; and element Q_3 is connected to the electrodes 3 and 4. If the three piezo electric elements Q_1 , Q_2 and Q_3 each have different fundamental frequencies, oscillations of three different frequencies may be generated by the oscillation generator without substituting different piezo electric elements for those in circuit.

Any one of the elements may be used to control the frequency of oscillation by adjusting the resonant frequency of the circuit 12-13 to correspond, or approximately correspond, to the fundamental frequency of

the element. For example, when piezo electric element Q_1 is to be used as a frequency control the resonant frequency of the circuit 12-13 is adjusted to equal or approximately equal that of Q_1 . In a similar manner any one of the elements Q_2 and Q_3 may be employed to control the frequency of the oscillations generated.

The oscillation generator embodied in this 10 invention may be employed in an arrangement where it is desired to obtain frequency controlled oscillations of large amplitude without resorting to the use of power amplifiers. When the piezo electric elements Q_1 , 15 Q_2 and Q_3 are so chosen that they all possess an identical fundamental frequency, oscillations of large amplitude are generated since the piezo electric elements all function simultaneously. Greater power output may then 20 be obtained from a piezo electric crystal controlled oscillation generator. Obviously some of the amplifiers usually necessary to increase the amplitude of the oscillations before they are impressed upon the large capacity power amplifier are eliminated in arrangements employing the oscillation generator of this invention. Greater operating efficiency is thus obtained.

While I have described my invention in one 30 of its preferred embodiments, I desire that it be understood that modifications of this invention may be made and that no limitations upon the invention are intended other than are imposed by the scope of the appended claims.

What I claim as new and desire to secure by Letters Patent of the United States is as follows:

1. A high frequency oscillation generator 40 comprising in combination, a thermionic discharge device having a cathode electrode, a plurality of control electrodes and an anode electrode, input and output circuits connected with said electrodes and separate mechanically vibratile frequency control elements 45 connected to each of said control electrodes and to said cathode electrode.

2. A high frequency oscillation generator comprising in combination, a thermionic 50 electron discharge device having a cathode electrode, a plurality of control electrodes and an anode electrode, input and output circuits connected to said electrodes and mechanically vibratile elements associated with 55 said input circuits, said elements being connected between each of said control electrodes and the cathode electrode.

3. In a high frequency oscillation generator the combination of a thermionic elec- 60 tron discharge device having a cathode electrode, a plurality of grid electrodes and an anode electrode, an output circuit including an inductance and an electrostatic capacity connected to said anode electrode and said 65 cathode electrode, a plurality of piezo elec-

tric crystals, individual piezo electric crystals being connected between said grid electrodes and between each of said grid electrodes and said cathode electrode.

4. A high frequency oscillation generator 70 comprising in combination, a thermionic electron discharge device having a cathode electrode, a plurality of control electrodes and an anode electrode, input and output circuits connected to said electrodes and mechanically vibratile elements associated with 75 said input circuits, individual elements being independently connected between said control electrodes and between said control electrodes and said cathode.

5. In a high frequency oscillation generator 80 the combination of a thermionic electron discharge device having a cathode electrode, a plurality of grid electrodes and an anode electrode, an output circuit including an inductance and an electrostatic capacity connected to said anode electrode and said cathode electrode, a plurality of piezo electric crystals 85 each having a different fundamental frequency, individual piezo electric crystals being connected between said grid electrodes and between each of said grid electrodes and said cathode electrode.
